Attorney.

UNITED STATES PATENT OFFICE

2,007,534

EASEL

William S. Kapnek, Philadelphia, Pa., assignor to
Modern Easel Company, a corporation of
Pennsylvania.

Application February 28, 1934, Serial No. 713,300

7 Claims. (Cl. 248—37)

The invention relates to improvements in easels, and is especially applicable to that type of easel in which a frame for photographs, mirrors or the like, becomes in itself a part of the easel structure, and in which such frames are provided with a back which is usually removably associated with the frame and which back is provided with an easel prop and means for securing its angular adjustment.

10 The especial purpose of the invention is to provide simple and efficient means associated therewith for securing the adjustment between said back and a prop and also for facilitating with great ease very slight movements of adjustment.

15 As the entire adjustable supporting means is associated with the removable back, it follows that these backs with the adjustable supporting mechanism may be provided to fit standard or stock frames without any change or alteration 20 therein.

25 Referring to the drawing, which illustrates merely by way of example, suitable means for the embodiment of my invention;—

Fig. 1 is a rear perspective view of the complete frame and easel embodying my invention.

30 Fig. 2 is a side elevation, on a larger scale and partly in section, of the removable back with the easel arrangement.

Fig. 3 is a fragmentary section on a still larger scale, on line 3, 3 of Fig. 4.

Fig. 4 is a section on line 4, 4 of Fig. 3.

Fig. 5 is a fragmentary perspective with part broken away.

Fig. 6 is a front perspective of the complete 35 frame and easel on a smaller scale.

Similar numerals refer to similar parts throughout the several views.

In the example shown, the frame 10 is usually 40 of metal and provided with front and rear flanges 11 and 12 forming a channel for receiving the picture or mirror and the back piece. The rear flange is omitted at the bottom of the frame to provide a passage for the insertion and withdrawal of the picture, or mirror and back piece.

45 All of which is well known in the art.

In accordance with the present invention the back piece 13 may be made of any stiff sheet material, such as metal, wood, cardboard or the like, and is adapted to be inserted in the frame 50 under the rear flanges 12, after the other elements have been assembled therein.

The present invention comprises the construction, arrangement and association of the prop and adjusting means with this back piece.

55 To this back piece 13 is secured, by a hinge, as

at 14, the upper end of the prop 15. A strut element 17 is also secured to the back piece 13, at a point below the hinge 14, by the hinge 18. The other end of the strut element 17 is pivotally secured, or hinged, as at 19, to a slide element 20 having a slot 21 extending from its free end to near its other end which is connected to the pivot 19.

The prop 15, in the present example, is made of two flanged sheet metal elements telescoping together so as to leave a space between said sheets; the under sheet having the longitudinal slot or channel 22 cut therein. This slot 22 is adapted to receive the slide element 20, while the pivot 19 is made to extend on each side of said slide member beneath the opposite margins of the slot so as to maintain said slide member within the slot. It will be obvious from an inspection of Fig. 2, that the movement of the slide member 20 in said slot will change or adjust the angle 20 between the back piece 13 and the prop 15.

As convenient and effective means for locking the parts in the desired position of adjustment I provide the following mechanism.

In about the middle part of the opposite or upper wall 15' of the prop member 15, from that containing the channel 22, I provide an opening for receiving the flanged housing element 23, which provides a housing for the cam lever 24. This lever 24 is provided with a pivot 25 having extensions which project from each side of the cam lever 24, through slots or enlarged openings 26, in the sides of said housing element, and spaced from the flange 27 of said element 23. The housing element 23 fits snugly in the slot 21 of slide member 20 so that the flanking parts of said slide member may move freely on each side of the housing element. This slide member is also positioned to slide between the extensions of pivot 25 and the flange 27 of housing element 23.

Because of the form and arrangement of the slots 26 in the sides of housing element 23 through which project the extensions of the pivot 25, the cam portion 28 of lever 24, normally rests 45 upon the bottom 29 of the housing element 23. It follows that as the enlarged portion of the cam moves in the direction of the arrow shown in Fig. 4, the pivot 25 secured thereto is raised or moved toward the flange 27 of the housing 30 50 23, and thus serves to clamp the slide member 20 against the housing flange or against the wall 15' supporting same, as the case may be. Thus by pushing down the free end of lever 24, after the slide member is brought into position of ad-

justment, the parts are securely locked in said position.

What I claim is:—

- 5 1. The combination of a frame and easel, the easel comprising a back piece removably secured to the frame, a prop pivotally secured to the back piece, a strut for adjusting the angle between the prop and back piece and means including a member pivoted to the strut and in slidable engagement with the prop, a housing secured to the prop and a cam seated in the housing and operating to lock the sliding member to the prop.
- 10 2. The combination with a frame, a prop having pivotal relation therewith, a strut having pivotal relation with both the frame and the prop, the prop comprising two parallel walls forming a passage therebetween and a slide pivoted to the strut movable in said passage as means for adjusting the angle of the prop with respect to the frame and means comprising a clamp connected with the prop for locking the parts in desired position of adjustment.
- 15 3. The combination of a frame and a back piece removably secured to the frame, a prop pivotally secured to the back piece, a strut and a slide member hinged thereto, said strut and slide member connected with the prop and back piece for adjusting their angular relationship, the slide member provided with a longitudinal
- 20 30 channel, a housing connected to the prop and projecting into said channel, and means comprising a cam seated in the housing for locking the parts in required position of adjustment.
- 25 4. In an easel, the combination of a frame, a back piece removably secured thereto, a chan-

nelled prop in hinged relation with the back piece, a strut also in hinged relation with the back piece, a channelled slide member hinged to the strut and slidable in the channel provided in the prop, a housing connected with the prop and projecting into the channel of the slide and a cam member seated in the housing and operating to clamp the slide member to the prop.

5. In an easel, the combination of a frame, a back piece removably secured thereto, a prop in hinged relation with the back piece, a strut also in hinged relation with the back piece, a slide member hinged to the strut and slidable in a channel provided in the prop and a cam member associated with the prop and provided with projecting pivot extensions adapted to clamp the slide member in position of adjustment.

6. The combination of a frame, a prop pivoted to the frame and provided with a longitudinally extending slot, a strut pivoted to the frame, a slide movable in the slot of the prop, a pivot pin connecting the slide to the strut, said pin having ends projecting, in a plane parallel with the prop, on each side of the slide beyond the side margins of the slot, and means for locking the slide in position of adjustment with the prop.

7. In an easel, the combination of a frame, a slotted prop pivoted to the frame, a strut pivoted to the frame, a slide pivoted to the strut and slidable in a slot provided in the prop, a flanged housing secured in the prop and a cam seated in the housing, said cam provided with flanking pin projections for locking the slide in desired position of adjustment.

WILLIAM S. KAPNEK. 35
